UNITED STATES PATENT OFFICE.

ALFRED M. LANE, OF ST. LOUIS, MISSOURI.

CASEMENT WINDOW.

Application filed March 8, 1929. Serial No. 345,262.

This invention relates to casement windows. The principal objects of the present invention are to produce a strong and rigid light-weight metal casement window of simple construction and pleasing appearance which can be cheaply manufactured; to reduce the number of parts of the window; and to provide for the easy assemblage of these parts to form window casings and sashes of such cross-sectional shape that they will readily accommodate metal weatherstrips and render easy the application of such strips thereto. The invention consists principally in the weatherstripped metal casement window; and it also consists in the parts and in the arrangements and combinations of parts hereinafter described and claimed.

In the accompanying drawings, which form part of this specification and wherein like symbols refer to like parts wherever they occur,

Fig. 1 is an exterior side view of a weatherstripped casement window embodying my invention;

Fig. 2 is a vertical cross-section through the window on the line 2—2 in Fig. 1;

Fig. 3 is a horizontal cross-section through one side of the window frame and the adjacent inner side rail of the sash supported thereon, the section being taken on the line 3—3 in Fig. 1; and

Fig. 4 is a horizontal cross-section through the meeting rails of the sashes of said casement window.

Referring to the accompanying drawings, the invention is illustrated in connection with a double casement window comprising a metal window casing or frame A and two metal window sashes B that are secured to the respective jamb members of said frame by means of hinges 1 so as to swing outwardly.

The window frame A comprises metal jamb members 2 connected at their upper ends by a metal head member 3 and at their lower ends by a metal sill member 4. Each of the jamb members 2 of the window frame preferably comprises a main body portion of substantially flat-section having its inside and outside marginal edges shaped to form ornamental beads or moldings 5. Each jamb member 2 is also provided on its sash supporting face with an outstanding longitudinal flange 6 adapted, in the closed po-

sition of the sash hinged on said jamb member, to overlap the outside edge of the inner side rail of said sash. The flange 6 of each jamb member 2 is of substantially L-shaped section; that is, it comprises an outstanding web portion formed integral with the jamb member and provided at its outer edge with a rearwardly extending lateral flange adapted to form a vertical channel or recess 7 adjacent to the outside face of the inner side rail of said sash.

The head member 3 of the window frame A preferably comprises a main body portion which extends horizontally from jamb to jamb and is provided along its inside and outside edges with ornamental beads or moldings 8 similar to the ornamental beads or moldings 5 along the inside and outside edges of the two jamb members 2. The main body portion of the head member is upwardly offset adjacent to the upper outside corners of the sashes to form a longitudinal channel 9 in the underside of said head member. A metal strip 10 has a horizontal base flange secured in said channel by means of screws 11 and is provided along its outside marginal edge with a downwardly and outwardly inclined flange which constitutes a drip edge.

The sill member 4 of the casement window frame A comprises a metal member of substantially inverted channel-shaped section which extends horizontally from jamb member to jamb member. The outer portion 12 of the web of the sill member 4 slopes downwardly to provide for drainage; and the inner portion of said web is offset upwardly and is provided along its outer edge with an outwardly extending horizontal flange 14 that is spaced above and overhangs the inner marginal portion of the sloping portion 12 of the web of said sill member.

Secured to the sash opposing faces of the head, sill and jamb members of the casement window frame adjacent to the inside faces of the sashes are metal sash stops of moldings 15 of substantially channel-shaped cross-section. The channel-shaped stops 15 are positioned on the head, sill and jamb members of the window frame with their channels facing the sash opposing faces of said members and with their inside flanges seated within longitudinal grooves 16 provided therefor in said members. The stops 15 are clamped to the head, sill and jamb members

with their inside flanges seated within the longitudinal grooves 16 provided therefor by means of fastening screws 17. At the sash opposing side of the stops 15 the webs 5 thereof are extended, as at 18, outwardly beyond the outer flanges thereof to form a longitudinal recess 19 adjacent to the inside faces of the top and side rails of the sashes.

The frame members 20 which form the 10 top bottom and side rails of the window sashes B are of substantially channel-shaped section, each of these members comprising side marginal flanges connected by a web which is provided along its outside corner 15 with a flange or abutment 21 which forms a seat for a sash pane 22. The window panes 22 are set in putty that is held in position by means of metal glazing strips 23 that are removably secured to the frame 20 members of the sashes by means of screws 24. The upwardly opening channels in the frame members which form the top rails of the sashes are closed by means of cover plates 26 that are rigidly secured to the webs 25 of the top rails by means of screws 27. The channels in the outer side rails of the two sashes B are closed by means of metal members 28 of substantially T-shaped cross-section which form the meeting rails of said 30 sashes. The stems of the T-shaped meeting rails 28 cover the channels in the outer side rails of the respective sashes and are rigidly secured thereto by screws 29. The T-shaped meeting rails are positioned on the respective 35 sashes with the inner side flange of one meeting rail overlapping the outside face of the outer side rail of one sash and with the inner side flange of the other meeting rail overlapping the inside face of the outer side 40 rail of the other sash. With this arrangement of the T-shaped meeting rails the outer side flange of the rail on one sash overlaps the outer side rail of the other sash in the closed position of said sashes. The outside 45 flanges of the bottom rails of the sashes terminate at their lower edges in inwardly extending portions 30 which extend beneath the outwardly extending flange 14 of the sill member 4 of the window frame in the closed position of said sashes.

The joint between the top rails of the sashes B and the head member 3 of the window frame A is rendered weatherproof and dustproof by means of a weatherstrip 55 31 secured to the underside of said head member. Said weatherstrip preferably comprises a strip of resilient sheet metal whose outer side marginal portion is doubled under to provide a sealing flange 32 adapted to resiliently engage the top surface of said cover plates 26 for the top rails of the sashes. The head strip 31 has its outer margin offset upwardly and clamped within the channel 9 of the head member 3 by means of the drip strip 10. The inner marginal portion of the

head strip is bent downwardly and thence rebent upwardly to provide a sealing flange 33 which fits within the longitudinal recess 19 in the outside face of the head stop 15 and is adapted to resiliently engage the adjacent inner faces of the top rails of the sashes in the closed position thereof.

The joints between the window jambs 2 and the inner side rails of the sashes are weatherproofed by means of weatherstrips 75 34 secured to the sash opposing faces of the jambs in position to cooperate with the inner side rails of the sashes in the closed positions thereof. Each of the jamb strips 2 preferably comprises a sheet of resilient sheet metal whose inner side marginal portion is doubled-back on the inner face of the strip and is thence bent outwardly away from the body portion of the strip and is thence rebent towards said body portion 80 to provide a sealing flange 35, which fits within the longitudinal recess 19 in the outside face of the jamb stop 15 and resiliently engages the inside face of the inner side rail of the sash in its closed position. The 85 longitudinally doubled inner side marginal portion of the jamb strip 34 extends beneath the outside flange of the jamb stop 15 and is secured to the jamb preferably by means of screws 36 located beneath said stop. The main body portion of the jamb strip 34 extends outwardly between the jamb and the inner side rail of the sash and terminates at its outer side edge in a sealing flange 37 which is disposed at an oblique angle to the 90 face of the jamb in position to resiliently engage the edge of the outside flange of the inner side rail of the sash in the closed position thereof. The free outer edge of the sealing flange 37 of the jamb strip fits loosely 95 within the longitudinal recess 7 formed by the L-shaped flange 6 on the jamb member and is thus concealed and protected by said flange.

The joint between the bottom rails of the sashes and the sill member 4 of the window frame is sealed by means of a weatherstrip 100 38 comprising a resilient strip of metal which rests flatwise on the upper surface of the outwardly projecting flange 14 of said sill member and is provided along its outside edge with a doubled-under sealing flange 39 which extends beneath said overhanging flange in position to resiliently engage the inwardly extending portions 30 at the lower edges of the bottom rails of the sashes in the closed positions of the latter. The flat body portion of the sill strip 38 is firmly clamped down upon the outwardly projecting flange 14 of the sill member 4 by 105 means of a clamping plate 40 which is secured in position by screws 41.

The joint between the T-shaped meeting rails 28 of the sashes is sealed by means of a weatherstrip 42 comprising a resilient strip 110

of metal of substantially Z-shaped cross-section. The meeting rail strip 42 is mounted on the meeting rail of one sash with its web portion disposed opposite the stem portion of said rail and with one flange 43 secured to the inside face of said rail and with the other flange located back of the outer flange of said rail and left free to form a sealing flange 44. With this arrangement of meeting rail strip when the sashes are closed the resilient sealing flange 44 of said strip bears against the inside face of the outer flange of the meeting rail to which it is secured and against the adjacent outside corner of the meeting rail of the other sash thereby sealing the joint between said sashes.

The hereinbefore described weather stripped casement window has numerous advantages. It reduces to a minimum the infiltration of air through the window; and it also serves to conceal and protect the sealing flanges of the weatherstrips. It utilizes a maximum number of frame members of the same cross-sectional size and shape, thereby reducing to a minimum the number of specially formed frame members required to a window; and it minimizes the time and expense of applying the weatherstrips.

Obviously, the hereinbefore described weatherstripped casement window admits of considerable variation without departing from the invention, and I do not wish to be limited to the precise arrangements shown and described.

35 What I claim is:

1. A casement window comprising a metal frame whose head and jamb members are provided with longitudinal recesses, a sash mounted in said frame for swinging movement, and weatherstrips mounted on said head and jamb members and having sealing flanges located in the longitudinal recesses in said members and adapted to resiliently engage the inside face of said sash in the closed position thereof.

2. A casement window comprising a metal frame whose head and jamb members are provided with longitudinal recesses, a sash mounted in said frame for swinging movement, weatherstrips mounted on said head and jamb members and having sealing flanges located in the longitudinal recesses in said members and adapted to resiliently engage the inside face of said sash in the closed position thereof, and a weatherstrip mounted on the sill member of said frame and having a sealing flange adapted to resiliently engage the lower rail of said sash in the closed position thereof.

3. A casement window comprising a frame and a sash mounted therein for swinging movement, and a weatherstrip mounted on the head member of said frame and provided with two sealing flanges adapted in the closed position of said sash to resiliently en-

gage, respectively, the top and one side face thereof.

4. A casement window comprising a frame and a sash mounted therein to swing outwardly, and a weatherstrip secured to the head member of said frame and having two sealing flanges adapted in the closed position of said sash to resiliently engage the respective top and inside faces thereof.

5. A cement window comprising a frame and a sash mounted thereon for outward swinging movement, and weatherstrips secured to the head and jamb members of said frame, the head strip having sealing flanges adapted to resiliently engage the top and inside faces of said sash in its closed position, and the jamb strip having sealing flanges adapted to engage the jamb opposing and inside faces of said sash in its closed position.

6. A double casement window comprising a frame and a pair of sashes mounted in said frame to swing outwardly, and weatherstrips secured to the head and jamb members of said frame and having sealing flanges adapted to engage the inside faces of the sash in the closed position thereof, said head and jamb members of said frame being provided with longitudinal recesses facing the inside face of said sash and adapted to receive the sealing flanges of the head and jamb strips.

7. A double casement window comprising a frame and a pair of sashes mounted therein to swing outwardly, a weatherstrip mounted in the head member of said frame and having sealing flanges adapted to resiliently engage the top and inside faces of said sashes in the closed position thereof, and weatherstrips secured to the jamb members of said frame and having sealing flanges adapted to resiliently engage the jamb opposing and inside faces of said sashes in the closed position thereof, the head and jamb members of said frame being provided with longitudinal recesses adapted to receive the sealing flanges of the strips mounted thereon.

8. A double casement window comprising a frame and a pair of sashes mounted therein to swing outwardly, a weatherstrip mounted in the head member of said frame and having sealing flanges adapted to resiliently engage the top and inside faces of said sashes in the closed position thereof, weatherstrips secured to the jamb members of said frame and having sealing flanges adapted to resiliently engage the jamb opposing and outside faces of said sashes in the closed position thereof, said head and jamb members being provided with longitudinal recesses adapted to receive the sealing flanges of the strips mounted thereon, and a weatherstrip secured to the meeting rail of one of said sashes and having a seal-

ing flange adapted to resiliently engage the meeting rail of the other sash in the closed position of said sashes.

9. A double casement window comprising a frame and a pair of sashes mounted therein to swing outwardly, a weatherstrip mounted in the head member of said frame and having sealing flanges adapted to resiliently engage the top and inside faces of said sashes in the closed position thereof, weatherstrips secured to the jamb members of said frame and having sealing flanges adapted to resiliently engage the jamb opposing and inside faces of said sashes in the closed position thereof, the head and jamb members of said frame being provided with longitudinal recesses adapted to receive the sealing flanges of the strips mounted thereon, the meeting rails of said sashes having portions adapted to overlap in the closed position of said sashes, and weatherstrips secured to the meeting rail of one sash and having a sealing flange adapted to resiliently engage the overlapping portions of said meeting rails in the closed positions of said sashes.

10. A double casement window comprising a frame and a pair of sashes mounted thereon to swing outwardly, and weatherstrips mounted on said jamb members and having sealing flanges adapted to engage the jamb opposing and inside faces of said sashes, the jamb members of said frame having longitudinal recesses therein facing the respective inside and outside faces of said sashes and adapted to receive the sealing flanges of said strips.

11. A metal casement window comprising a frame and a sash mounted therein for swinging movement, metal sash stops secured to said frame, said stops comprising channel-shaped members positioned on the frame with their channels facing the sash opposing surfaces thereof, the web portions of said stops extending outwardly beyond the outside flanges thereof to form longi-

tudinal recesses which face outwardly, and weatherstrips secured to said frame and having sealing flanges located in said recesses and adapted to resiliently engage the inside face of said sash in the closed position thereof.

12. A metal casement window comprising a frame and a sash mounted therein to swing outwardly, a drip strip secured to the head member of said frame, and a metal weatherstrip clamped to said frame between said drip strip and said head member and having a sealing flange adapted to resiliently engage the sash in the closed position thereof.

13. A metal casement window comprising a frame and a sash mounted therein to swing outwardly, a drip strip secured to the head member of said frame, and a metal weatherstrip clamped to said frame between said drip strip and said head member and having sealing flanges adapted to resiliently engage the top and inside faces of said sash in the closed position thereof.

14. A double casement window comprising a frame and a pair of metal sashes mounted on said frame for horizontal swinging movement, a weatherstrip secured to the inside face of one sash and extending outwardly across the meeting rail thereof and terminating at its outer margin in a sealing flange adapted to overlap the outside face of said sash in the closed position of said sashes, the meeting rail of the sash to which the strip is secured having a flange that covers the outer face of the sealing flange of said strip, and the meeting rail of the other sash having a flange adapted in the closed position of said sashes to overlap the inside face of the strip carrying sash and cover the portion of the strip secured thereto.

Signed at St. Louis, Missouri, this 5th day of March 1929.

ALFRED M. LANE.
